UNITED STATES PATENT OFFICE

WOLFGANG HERMANN, OF CHICAGO, ILLINOIS, ASSIGNOR TO METAL SPECIALTIES MANUFACTURING COMPANY, OF CHICAGO, ILLINOIS, A CORPORATION OF ILLINOIS

SPRAYING DEVICE FOR PAINTS, VARNISHES, ETC.

Application filed March 30, 1928. Serial No. 265,867.

This invention relates particularly to varnish-spraying devices, but the invention may be put to various analogous uses.

The primary object is to provide an efficient 5 compact unit, which embodies a portable motor and compressor of such compactness and efficiency as to enable the outfit to be carried by the operator while performing the spraying operation.

10 The invention is illustrated in a preferred embodiment in the accompanying drawings, in which—

Fig. 1 is a view partly in side elevation and partly in section of a spraying device embodying the invention; Fig. 2, a broken rear end view of the motor; Fig. 3, a broken view taken as indicated at line 3 of Fig. 1, the cap-plate of the rotary compressor being removed; Fig. 4, a sectional view taken as indicated at line 4 of Fig. 1, showing the inlet port of the compressor; Fig. 5, a view taken as indicated at line 5 of Fig. 1, and showing the outlet port of the compressor; Fig. 6, a broken vertical sectional view taken as indicated at line 6 of Fig. 1; Fig. 7, a section through the nozzle taken as indicated at line 7 of Fig. 1; Fig. 8, a broken vertical sectional view of the lower portion of the handle, taken as indicated at line 8 of Fig. 1; Fig. 9, a broken vertical sectional view of the compressor, slightly modified; Fig. 10, a section taken as indicated at line 10 of Fig. 9; Fig. 11, a broken sectional view showing details of the switch device; Fig. 12, a section taken as indicated at line 12 of Fig. 11; and Fig. 13, a front view of the trigger-device.

In the construction illustrated, A designates a motor-compressor unit having a horizontal axis; B, a handle supporting said unit; C, a nozzle extending forwardly from the unit A; and D, a can, or container, suspended from the nozzle.

The axis of the motor-compressor lies in 45 the longitudinal vertical plane of the handle and nozzle.

The motor-compressor unit A is shown as comprising a motor-casing A' containing an armature A² equipped with a shaft 1; a skeleton cap-plate A³ forming one end of the mo-

tor-casing; and a rotary compressor A⁴ carried by the cap-plate A³.

The motor-casing A' is shown with a rounded rear end wall 2 which is shown provided with air-inlets 2^a protected by wire-gauze screens 2^b which are secured over the openings by means of the plate 3.

The cap-plate A³ is shown as comprising a casting having a base-ring 4 and a series of flanges, or radiating fins 4^a which radiate from and support the cylinder 5 of the rotary compressor. The member A³ thus is a skeleton cap-plate having the cylinder of the compressor serving as the hub-portion of the spider. The cylinder has an integral end-wall 5^a from which extends a bearing 5^b for the shaft 1.

The skeleton cap-plate A³ of which the body of the compressor-casing forms a part may be of cast aluminum. In such case, it is preferred to insert in the cylinder a bottom-plate 6 which may be of brass, or steel, and a sleeve 7 of similar material which forms a circumferential lining for the cylinder of the compressor.

75 The armature-shaft 1 is supported in a bearing-sleeve 8 within the member 5^b.

The rotor of the compressor is designated 9. The rotor is disposed eccentrically with relation to the bore 10 of the compressor-chamber. The shaft 1 is shown provided at its extremity with a transverse slot 11 which is engaged by a screw, or pin, 12 with which the rotor is equipped. The rotor is of smaller diameter than the bore 10 of the compressor-chamber, and the inner wall of the sleeve 7 preferably is provided at one side with a concavity 7^a having a curvature corresponding with the curvature of the rotor.

90 The rotor is provided with oblique slots 9^a within which are located the sliding vanes 13.

The front end of the cylinder 5 is closed by a removable cap-plate 14 which is secured to the cylinder by means of screws 14^a. The cap-plate 14 is provided with a vertical lubricant chamber 15 whose upper end is closed by means of a plug 15^a. The lower end of the chamber 15 communicates through a passage 15^b with the central portion of the interior of the cylinder 5. The armature-shaft 100

1 is provided at one side with a longitudinal groove 1^a through which lubricant may find its way to the rear side of the rotor. Preferably disks of felt 16 are located in the lower portion of the chamber 15; and preferably the rotor 9 is provided with passages 17 extending therethrough parallel with the axis of the rotor and filled with felt. The felt serves to absorb oil and to yield the same as needed. The felt in the bottom of the chamber 15 prevents the oil from passing too quickly into the compressor-chamber.

The base-ring 4 of the cap-plate A³ is secured by means of long cap-screws 18 to lugs 19 with which the casing A' is provided internally near its rear end.

The cap-piece 14 of the compressor is provided at its lower portion with a hollow-tapped boss 20 with which the threaded shank 21 of the nozzle is connected.

The bottom wall 5^a of the compressor-chamber is provided (Fig. 4) with an admission port 22 which admits air to the compressor. The cap-piece 14 of the compressor chamber is provided (Fig. 5) with an outlet-passage 23 which leads to the passage 24 which communicates with the bore of the nozzle.

The armature-shaft 1 is equipped back of the cap-plate A³ with a fan 25 which serves to draw air through the screens 2^b at the rear end-wall of the motor-casing and expel the same through the spaces between the radiator fins 4^a, as indicated by the arrows in Fig. 1.

The handle B is hollow. Its upper end is shaped to form a cradle 26 which conforms to the lower side of the horizontally disposed motor-casing and which is secured to the motor-casing as by means of screws 27. The lower end-portion of the handle is equipped with laterally extending arms 28 which terminate in feet 28^a adapted to rest upon a support. The handle, in conjunction with the container D, is adapted to support the spraying device in standing position on a table, for example.

In the upper portion of the handle is housed a switch-device 29 which is mounted on an internal bracket 30 and which is equipped with a switch-lever 31 adapted to be actuated by a plunger-like trigger 32.

In the position illustrated in Fig. 1, the switch is open, the plunger 32 being moved forwardly by means of a spring 33. Any suitable switch mechanism may be employed which will work with a snap action in the breaking of a circuit, as hereinafter described. Current is supplied to the motor through conductors 34 and 35 which extend upwardly through the handle, the conductor 35 being divided and passing to the switch-points, so that when the switch is closed by actuating the trigger 22, current will be supplied to the motor; and when the pressure of the

finger is released, the circuit will be automatically broken.

The nozzle C is shown as comprising an inner member 36, an outer tip-member 37, and a ring 38 interposed between the rear end of the member 37 and a shoulder 39. The ring 38 has depending therefrom a member 38^a provided with a passage 38^b which communicates with a tube 38^c adapted to depend into the container D. The member 38^a is provided with a flange 40 which is secured to a closure 41 with which the container D is equipped.

The inner member 36 of the nozzle is provided at one side with a longitudinal groove, 42 which communicates with a space 43 between the tip-portion of the inner member 36 and the outer member 37. The rear end of the groove 42 communicates with an annular passage 44 which, in turn, communicates with the fluid-passage 38^b, as shown in Fig. 6. The passage 38^b is controlled by a needle-valve 45.

The bore 46 of the nozzle through which the air passes to the tip of the nozzle is provided at its front end with a reduced passage 46^a. As the air is emitted through this reduced passage, the effect is to cause a suction through the passage 42 so that liquid will be drawn to the point of the nozzle.

The can D has its top equipped with a threaded nipple 47 which receives the cap 41 of the attaching device. A gasket 48 serves to make an air-tight joint.

The wires 34 and 35 lead into the handle through a tubular boss 49 which is equipped with a flexible extension (close coiled wire) 50. The wires 34 and 35 form a part of a cord 51 which is equipped with a connector member 51^a.

The details of the switch-device 29 will be understood from Figs. 11 and 12. Embedded and securely housed between insulation-laminations 52 of a switch-block are a pair of spaced contacts 53 and 54 having contact segments 53^a and 54^a which are exposed in a chamber 55 formed by recessing the insulation-strips.

A metal roller 56 is adapted to travel back and forth along the arched top of the chamber 55 and in one position to bridge the space between the contact-points 53^a and 54^a and close the circuit. The switch-block is mounted upon a U-shape sheet-metal base 57 which is equipped with a threaded tubular nipple 57^a which extends through a hole in the bracket 30 and is secured by means of thin clamping-nuts 58.

The switch-lever 31 is supported on a pivot 59 carried by the member 57^a. It has a central ball-portion 60 located within the tubular member 57^a. A gasket-sleeve 61 which may be of rubber, or felt, is interposed between the ball-portion and the

tubular member 57^a, making a gas-tight connection, without interfering with the working of the trigger. The purpose is to prevent inflammable gases from reaching the switch-points.

The bracket 30 is carried by a trigger-plate 62 which is secured by means of screws 63 to bosses 64 with which the front upper portion of the handle B is provided.

The handle B may be of cast aluminum. As shown in Fig. 8, the front upper portion of the handle is furcated, or provided with a slot 65 to permit the insertion of the trigger device.

The inner end-portion of the switch-lever 31 and a member 66 which engages the roller 56 to form a sort of toggle-lever are adapted to actuate the roller. The member 66 has a slotted stem 66^a which forms a guide for a dished disk 67 which is backed by a spring 68. The inner end of the lever 31 is adapted to work within the slotted stem. When the lever 31 is actuated by pressing the trigger 32 rearwardly, the member 66 is swung forwardly about the roller 56 as a pivot, and, passing the dead center, forces the roller to travel rearwardly into contact with the contact-points 53^a and 54^a, thus closing the circuit. Upon the release of the trigger, the spring 33 returns the parts to the circuit-breaking position.

It has been found in practice that as soon as the circuit is broken, liquid will no longer be drawn from the container D; hence, it is unnecessary to employ a valve controlling the liquid passage.

In the operation of the improved spraying device, the device is held in the hand of the operator like a pistol. The weight of the motor and compressor unit, the nozzle, and the container are properly distributed with relation to the handle so that the device can be supported at arm's length, or partially so, without too great effort.

It will be noted that the longitudinal axis of the motor which corresponds with the axis of the armature-shaft points forwardly at a position above the hand of the operator, and the compressor is connected with the front end of the armature-shaft in position to deliver compressed air directly into the nozzle. The rotary compressor is direct-coupled to the armature and rotates at very high speed, so that a small compressor is thus capable of delivering fairly high pressure, say ten to twenty pounds per square inch.

In the circulation of the air which occurs in the operation of the device, there is some danger that inflammable gases may reach the commutator of the motor or the contact-points of the switch device. To guard against possible explosion, protecting features have been incorporated, as described above.

In the operation of the compressor, a con-

siderable amount of heat is developed. This heat is dissipated by currents of air driven by the fan 25 through the spaces between the radiator-fins 4^a.

In the oiling system provided for the compressor, lubricant is first conducted to the central portion of the rotor and is thrown outwardly by centrifugal action, reaching all parts. The blades, or vanes, 18 preferably are formed of hard fibre, but may be of any suitable material. They do not require the use of springs to maintain them in contact with the inner wall of the compressor cylinder. The rotor preferably has a very slight clearance at the point of contact with the concavity 7^a, sufficient to permit an exceedingly thin oil film to form between the surfaces. Thus the rotor may be in a sense regarded as a floating rotor.

In the modification shown in Figs. 9 and 10, the construction corresponds with the construction heretofore described, except that the armature-shaft 1 is shortened and is coupled to a separate extension 1^b upon which the rotor is mounted. Thus, the rotor has an individual shaft 1^b, and this preferably is coupled to the shaft 1 by means of a key 1^c which engages a slot 1^d. In this modification, both ends of the shaft-extension 1^b are journaled in bearings 69, one of which is in the bottom-plate 6, and the other of which is in the cap-plate 14 of the compressor-chamber.

The improved device is thoroughly adapted to its purpose. It has a large field of use for many purposes and in many situations where the large and expensive compressed-air supplying devices are not available. The organization of mechanisms and parts disclosed is such as to enable a self-contained, hand-carried spraying device, or unit, comprising a motor, compressor and nozzle to be used with the greatest practicability.

A modification of the present invention is disclosed in my pending application, Serial No. 228,336, filed October 24, 1927.

What I regard as new, and desire to secure by Letters Patent, is:

1. A hand-carried spraying-device comprising a motor having its front end provided with a removable cap-plate having a compressor-cylinder formed integrally therewith and having air outlet-passages around the cylinder, a rotor mounted in said cylinder and actuated by the armature of the motor, a fan disposed back of said cap-plate and actuated by the armature of the motor, a nozzle rigidly connected with the compressor, a container depending from said nozzle, and a handle having its upper portion secured to the lower side of the motor-compressor unit and equipped with a switch-device controlling the motor, said switch-device having a finger-piece located at the upper front portion of the handle.

2. A hand-carried spraying device comprising an electric motor having a horizontal axis and provided at its front end with a removable cap-plate, having a compressor-cylinder formed integrally therewith and having air outlet-passages around the cylinder, a rotor mounted in said cylinder and actuated by the armature of said motor, a fan disposed back of said cap-plate and actuated by the armature of said motor, a nozzle rigidly connected with the compressor and equipped with a depending container-supporting member and a liquid tube depending from said member, a handle having its upper end rigidly connected with the lower side of the motor casing, a switch mounted in the upper portion of said handle, a forwardly projecting trigger mounted in the upper portion of said handle controlling said switch, and a motor-controlling circuit having conductors extending through the handle and from the upper portion thereof into the motor casing, said circuit being controlled by said switch.
- 25 3. A device as specified in claim 2, in which said switch is equipped with a spring which serves to break the circuit when pressure upon the trigger is released.
4. A device as specified in claim 2 in which the switch is equipped with a depending switch lever which is engaged by the trigger, and in which the trigger is actuated by a spring which normally holds the switch lever in circuit-breaking position and the trigger in projected position.

WOLFGANG HERMANN.
